Primary Examiner — Mary Ann Calabrese*Assistant Examiner* — Catherine Ho(74) Attorney, Agent, or Firm — Myers Andras LLP;
Joseph C. Andras(57) CLAIM

The ornamental design for a lottery sign face, as shown and described.

DESCRIPTION

The single FIGURE is a front view of a lottery sign face showing the new design.

The broken lines in the FIGURE are for illustrating environmental structure that forms no part of the claimed design.
